UNITED STATES PATENT OFFICE

2,497,278

WORKTABLE ADAPTED FOR OFFICE WORK

Bengt Thronsen Söderlund, Stockholm, Sweden

Application February 27, 1947, Serial No. 731,237
In Sweden September 3, 1946

5 Claims. (Cl. 45—6)

1

The present invention refers to a work-table adapted for office work or the like, said work-table differing entirely, both in principle and with respect to the construction thereof, from the writing desks or combined writing and work-tables hitherto known.

The present office tables as devised substantially for writing work are not, for many reasons, serviceable in accordance with modern requirements, among which reasons the following may be pointed out. The table-top of said tables is frequently encumbered with a lot of objects which are required so frequently as to make it unpracticable to keep them stored in the drawers. The working space is restricted by these objects, which may be constituted by letter baskets, pencil stands, ink stands, stamps, and so forth. The drawers also are unsatisfactorily utilized in an ordinary writing desk provided with cabinets, since generally only an outer portion of the drawers is effectively used, depending on the trouble of pulling out a long drawer to the whole of its extent. Generally, nothing at all is stored in the inner portion of the drawers of the cabinets, or should anything be stored therein, the material in consideration is such that would not be used, whereby an expensive space is occupied, which should be free to make room for the legs of the person working at the table. Add to this that a drawer or extension leaf pulled out of the cabinet obstructs the drawers therebeneath. If a middle drawer provided in the table top is to be opened by more than a few decimeters, it will be necessary to stand up from the writing desk. Furthermore, the working range of an ordinary work-table is limited. A writing desk is too high for typewriting, and a typewriter table is inconveniently low for hand-writing. It is true that tables have been provided with foldable machines, but these tables are in the first place limited with respect to the use thereof by the fact that the cabinet is only adapted for the machine in question, and, secondly, these tables are expensive in manufacture. All of these drawbacks are entirely obviated by the work-table in accordance with the invention.

The distinguishing feature of the work-table according to the invention substantially resides in the fact that the table top consists of a frame enclosing displaceable and foldable leaves, which cover one or more compartments accessible from the upper side of the table-top.

The accompanying drawings illustrate examples of a form of embodiment of the invention.

Fig. 1 is a perspective view of the table look-

2

ing obliquely from the front, and Fig. 2 is a similar view of the table looking obliquely from the rear. Fig. 3 shows the table as viewed from the front, and Fig. 4 is a plan view thereof. Fig. 5 shows the table viewed from the end thereof. Fig. 6 is a section of a leaf on line VI—VI in Fig. 4, and Figs. 7 and 8 are similar sections on lines VII—VII and VIII—VIII in Fig. 4. Fig. 9 is a section on line IX—IX in Fig. 4, and Fig. 10 is a section on line X—X in the same figure. Fig. 11, finally, is a cross section through the table-top on line XI—XI in Fig. 4.

According to the drawing, 1 designates a frame confining the table-top. This frame need not necessarily enclose the whole table-top, but may also be conceived as being open for a distance at the front. 2 denotes a supporting fillet extending in the longitudinal direction of the table and dividing the table-top into two sections containing various compartments. The rear compartment or compartments are deeper by the provision of a trough-like box 3 underneath the frame, said box being constructed so that the sum of two opposite angles between the bottom and the sides of the box is always greater than 180°.

The rear compartment or compartments are intended, inter alia, for forms, letter baskets, card systems of various kinds, suspension folders, and so forth. They are covered by a number of displaceable leaves 4 and 5 respectively. Of these leaves, the displaceable leaves 4 are formed as hinges 6 engaging one another and covered by a rubber mat 7. The hinges have shafts 8 extending therethrough, said shafts being angularly bent at the ends thereof and formed into bearings 9 for rollers 10 carrying the hinges. The rollers 10 of the leaves are adapted to run in channels 11, which are bent approximately by 90° at the ends of the table and continue down to the box-like compartment 3. The flexible leaves 4 may thus be displaced laterally down into the table so as to uncover corresponding openings for the compartments therebeneath.

The intermediate leaves 5 are not flexible, and the rubber mat 7 is braced up here by a piece of sheet-metal 12 arranged on shafts 13 carrying the leaf. The ends of said shafts are adapted to carry the wheels 10. The leaves 5 are displaceable in a lateral direction, after one or both of the leaves 4 have been thrust down into the table.

The front compartment or compartments are intended, inter alia, for pencil stands, ink stands, stamp stands, note blocks, calendars, number registers, telephones, and so forth. The compartments are made so as to permit as many com-

binations as possible. The compartments are covered by displaceably and swingably arranged leaves 14. These leaves are supported by plates 15 having sleeve-shaped members 16 arranged on the insides of the leaves running on the upper edges of said plates, whereby the leaves may be pulled out in the ordinary manner. Running within the sleeves 16 are bars 17 swingably mounted at the one end thereof by means of pins 18 engaging lugs 19 secured in the supporting fillet 2. By this means the leaves 14 are also rendered foldable. Obviously, there is nothing that would prevent these leaves also from being made flexible, so that they may be thrust in their entirety into the table-top, if desired.

The side portions of the leaves 14 may also be provided with recesses 21, whereby it will be possible to fold down the leaves in their pulled-out position into a convenient inclined position suitable for writing. Here, the recesses 21 are adapted to grip about the frame portion 1. A condition for this folding-down operation is, however, that the plates 15 are removed.

By the removal of the corresponding pins 18, a leaf 14 may be removed, and a typewriter or calculating machine may then be inserted, said machines being thus placed on a suitable working level.

The table is supported by plates 20 bent into legs and so arranged as to occupy a space as small as possible underneath the table-top. The construction of the table permits without difficulty the arrangement of a central lock common to all of the leaves, said lock being not shown in the drawing, however.

The advantages of the work-table according to the invention are evident. There are no drawers to open and to close, and the whole equipment is immediately accessible. The surface of the table-top is entirely free, and a larger working space is obtained, since encumbering cabinets are conspicuous by their absence. Only one type of table will have to be manufactured in a few sizes, since the same table is just as serviceable both as a typewriter table and as an ordinary writing desk. Every table can be readily altered as desired. The consumption of material for the table is very small, and in combination with the simple construction, without any drawers or a suspension, the table will be very inexpensive in manufacture. By the fact that all of the parts comprised in the table permit of being piled on top of each other, the costs of storage, freight, and packing will be low.

The invention should not be regarded as confined to the form of embodiment as herein illustrated and described, it being possible to modify the same within the scope of the invention, especially as regards the construction of the details. For example, the sides and the bottom may be preferably manufactured integral from Bakelite in one trough-like piece, and all of the leaves may be made displaceable in the same direction.

Having now described my invention, what I claim as new and desire to secure by Letters Patent is:

1. In an office table, in combination, supporting legs, a generally rectangular frame mounted on said legs, said frame having a member extending longitudinally thereof dividing the frame into two portions, a bottom supported from the lower side of said frame to form two compartments, one forward of said longitudinal member and one rearward thereof, and a plurality of slidable cover means for each said compartment,

the cover means for the rear compartment being movable in a direction parallel to said longitudinal member and those for the forward compartment being movable in a direction perpendicular to said longitudinal member.

2. In an office table, in combination, supporting legs, a generally rectangular frame mounted on said legs, said frame being comprised of members of substantial depth, a member extending longitudinally of said frame and dividing the frame into two portions, a bottom supported from the under side of said frame to form two large compartments, one forward of said longitudinal member and one rearward thereof, partition members extending in a direction perpendicular to said longitudinal member and subdividing the forward compartment into a plurality of smaller compartments, and slidable cover means for said compartments, said cover means for the rear compartment being movable in a direction parallel to said longitudinal member, said cover members for the forward compartment being mounted on said partition members and being movable in a direction perpendicular to said longitudinal member.

3. In an office table, in combination, supporting legs, a generally rectangular frame mounted on said legs, said frame being comprised of members of substantial depth, a member extending longitudinally of said frame and dividing the frame into two portions, a bottom supported from the under side of said frame to form two large compartments, one forward of said longitudinal member and one rearward thereof, and slidable cover means for said compartments, said cover means for the rear compartment being mounted on the rear frame member and said longitudinal member and being movable in a direction parallel to said longitudinal member, said cover members for the forward compartment being movable in a direction perpendicular to said longitudinal member.

4. In an office table, in combination, supporting legs, a generally rectangular frame mounted on said legs, said frame being comprised of members of substantial depth, a member extending longitudinally of said frame and dividing the frame into two portions, a bottom supported from the under side of said frame to form two large compartments, one forward of said longitudinal member and one rearward thereof, partition members extending in a direction perpendicular to said longitudinal member and subdividing the forward compartment into a plurality of smaller compartments, and slidable cover means for said compartment, said cover means for the rear compartment being mounted on the rear frame member and said longitudinal member and movable in a direction parallel to said longitudinal member, and the cover members for the forward compartment being mounted on said partition members and being movable in a direction perpendicular to said longitudinal member.

5. In an office table, in combination, supporting legs, a generally rectangular frame mounted on said legs, said frame having substantial depth, a member extending longitudinally of said frame and dividing the frame into two portions, a bottom supported from the under side of said frame, said bottom having a deeper portion at the rear thereof thereby forming a shallower forward compartment and a deeper rearward compartment, means extending perpendicular to said longitudinal member to subdivide said forward compartment into a plurality of smaller

compartments, slideable means operable in a direction perpendicular to said longitudinally extending member to cover said smaller forward compartments, said means being removable at will and means slideable on said longitudinal extending member and the rear member of said frame in a direction parallel to said longitudinal extending member to cover said rear compartment, a portion of said cover means being movable to permit sliding movement of the remainder 10 of said means.
